CLAIM

The ornamental design for a household robot, as shown and described.

DESCRIPTION

FIG. 1 is a front perspective view of a household robot, showing our new design in a first state;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is a rear perspective view thereof;

FIG. 9 is a front perspective view of the household robot, showing our new design in a second state;

FIG. 10 is a front view thereof;

FIG. 11 is a rear view thereof;

FIG. 12 is a left-side view thereof;

FIG. 13 is a right-side view thereof;

FIG. 14 is a top view thereof;

FIG. 15 is a bottom view thereof; and,

FIG. 16 is a rear perspective view thereof.

The broken lines illustrating portions of the household robot that form no part of the claimed design.

The center portion of the household robot can be moved upward and downward as shown in FIGS. 1-8 and FIGS. 9-16.
